UNITED STATES PATENT OFFICE

122,580

DESIGN FOR A POOL TABLE

Charles A. Wendt, Milwaukee, Wis.

Application July 3, 1940, Serial No. 93,409

Term of patent 7 years

To all whom it may concern:

Be it known that I, Charles A. Wendt, a citizen of the United States and resident of Milwaukee, in the county of Milwaukee and State of Wisconsin, have invented a new, original, and ornamental Design for Pool Tables, of which the following is a specification, reference being had to the accompanying drawing, forming part thereof.

The figure is a perspective view of the pool table, showing my new design.

I claim:

The ornamental design for a pool table, as shown.

CHARLES A. WENDT.
